Patented July 5, 1966

205,186

SNOW SKATE

Martin E. Koskela, Garden City, and James J. Byrne,
Birmingham, Mich., assignors to Byrne Plywood Com-
pany, Royal Oak, Mich., a corporation of Michigan

Filed May 10, 1965, Ser. No. 85,204

Term of patent 14 years

(Cl. D34—14)

FIGURE 1 is a perspective view of a snow skate showing our new design.

FIGURE 2 is a side elevational view thereof.

FIGURE 3 is a bottom plan view thereof.

The dominant features of our design reside in the portions shown by means of full lines in the drawing.

We claim:

The ornamental design for a snow skate, substantially as shown and described.
